EUCLID I. LA CHAPELLE, OF BROCKTON, MASSACHUSETTS

ART OF MAKING SHOES

Application filed April 17, 1929. Serial No. 355,785.

The term "shoe" occurring in the specification and in the claim is to be interpreted to include the term "boot"; and is to be interpreted to include within its broadest meaning a shoe upper attached to an insole.

This invention relates to shoes having insoles and more particularly to such shoes as of the well known Goodyear welt type.

In the manufacture of shoes of the Goodyear welt type the marginal forepart portion of the insole curls upwardly within the shoe under the influence of the strain incident to stitch setting in the formation of the inseam by the welt shoe sewing machine. This objectionable feature is due to the fact that under the effect of such strain the plane face of the insole, within the inseam line, is moved to some extent from the bottom of the last; and is due to the fact also that the between substance or sewing rib of the insole is forced outwardly against the marginal portion of the insole. Even at the lasting operation the marginal forepart portion of the insole is forced upwardly and notably so at the little toe lateral side of the last as the marginal forepart portion of the insole usually extends beyond the edge of the last at that side. Moreover, lasts intended for shoes of the Goodyear welt type have somewhat rounded bottoms so as to have the marginal portion of the insole on a lower plane than that of the between substance or sewing rib of the insole and out of the way of the curved needle of the welt shoe sewing machine. This condition adds also to the curling up of the marginal portion of the insole. During the time of wear the plane face of the insole, within the inseam line, is depressed under the weight of the wearer and the inner bottom of the shoe is far from being comfortable as the curled up edge of the insole is thereby forced against the foot.

The objective of my present invention is to render shoes of the Goodyear welt type more comfortable and more flexible by providing an insole, incorporating the same in a shoe and in due time cutting off part of the marginal forepart portion of the insole in the shoe.

As shown in the drawings:

Fig. 1, is a bottom plan view of an ordinary insole adapted to a shoe of the well known Goodyear welt type.

Fig. 2, is a top plan view of the insole shown in Fig. 1.

Fig. 3, is a shoe in which is incorporated the ordinary insole shown in Figs. 1 and 2, with a cutting implement shown after the start of its cutting operation upon the marginal forepart portion of the insole.

Fig. 4, is the shoe shown in Fig. 3, with the cutting operation completed at both lateral sides of the forepart of the insole.

Fig. 5, is a section taken on line 5—5 Fig. 4.

Fig. 6, is a perspective view of the cutting implement.

As further shown in the drawings:

1, represents an ordinary welt shoe insole; and as shown in Fig. 4, the insole is beveled at 2, along the marginal forepart portion thereof in accordance with the practice of the novel improvement in the art of making shoes herein disclosed whereby the inner bottom of the shoe is made more comfortable and more flexible and more on a level plane from edge to edge than in the case of ordinary shoemaking. As shown, the beveling of the insole takes place after the incorporation of the insole in the shoe by means of the cutting implement 3, the handle of which is curved to permit of insertion into the forepart of the shoe. The said cutting implement consists of the shank portion 4, which supports two cutting blades 5, and also a guide 6, which is adapted to engage the edge face of the insole in the shoe whereby the cutting means may be held at uniform distance from the edge face of the insole during its cutting action and which also serves as a lining guard whereby the lining of the upper or the upper proper is held from contact with the cutting means. The under faces 7 and 8 of the shank portion of the said cutting implement are angularly disposed relatively to each other whereby one of the cutting means may be used at one side of the shoe while the remainder of the said cutting means is held above the plane face of the insole and out of contact therewith.

The extreme toe-end of the insole is not beveled and need not be as the foot does not contact with the insole at that point.

The degree of bevel should, preferably, extend from the inseam line to and including part of the edge face of the insole. It is to be appreciated that for best results the insole should be of substantial thickness.

Having thus explained the nature of my invention and disclosed the best form of practice now to me known, what I claim as new and desired to secure by Letters Patent of the United States is:

That improvement in the art of making shoes of the Goodyear welt type which consists in reducing the thickness of the marginal forepart portion of an insole in a shoe of that type by cutting off, from within the shoe, a portion of the said insole from a substantial distance of its edge face to and including part of its edge face.
